UNITED STATES PATENT OFFICE.

DAVID T. WILLIAMS, OF PATERSON, NEW JERSEY, ASSIGNOR OF ONE-HALF TO FRANK L. CONNABLE, OF WILMINGTON, DELAWARE.

FEED-WATER HEATER.

1,078,026.

Specification of Letters Patent. Patented Nov. 11, 1913.

Application filed November 14, 1912. Serial No. 731,294.

To all whom it may concern:

Be it known that I, DAVID T. WILLIAMS, a subject of the King of Great Britain, residing at Paterson, in the county of Passaic and State of New Jersey, have invented certain new and useful Improvements in Feed-Water Heaters, of which the following is a specification.

This invention relates to means for utilizing the heat of the smoke and gases passing through the smoke-box of a boiler of the locomotive class in heating the feed-water. Its principal object is so to construct a system for conducting the water through the smoke-box as to permit of ready access to the interior of the smoke-box for the purpose of inspection and repairs and yet obtain a feed-water heating system which shall be a thoroughly efficient and reliable and otherwise practical adjunct of a boiler.

According to this invention, a feed-water heater is pivoted in the smoke-box so that its pivoting axis extends transversely of the smoke-box, the heater having a bearing at each point where said axis penetrates the wall of the smoke-box, and the inlet and outlet connections are connected with the heater respectively at said bearings. Preferably said axis is substantially coincident with the central line of the heater and a diameter of the smoke-box, and the heater's area approximates as nearly as practicable the transverse area of the smoke-box whereas its front-to-rear thickness is appreciably less. Thus, while in working position (with one broad face forward) the heater exposes the maximum amount of surface to the heat of the smoke and gases flowing through the smoke-box, when turned ninety degrees (more or less) easy access to the interior of the smoke-box behind the heater is allowed. I further provide, back of the heater, an adjustable means for varying at will the course of the smoke and gases with respect to the heater, so as to subject the heater to more or less heat derived from such smoke and gases, according as the circumstances require.

The heater, *per se*, is further constructed in a way to obtain the maximum amount of radiating surface, to make it as strong and durable as possible, to facilitate the assembling of its various parts and their preservation in proper working order and to make

it adaptable to various types of smoke-box constructions.

In the accompanying drawings, Figure 1 is a longitudinal vertical sectional view of a locomotive boiler and smoke-box and of the improved feed-water heating system, the plane of the section being slightly to the right of the pivoting axis of the heater; Fig. 1^a is a sectional view of the heater in a vertical plane through the innermost row (front to rear) of tubes; Fig. 2 is a view partly in front elevation and partly in section on line *x*—*x* of Fig. 1; Fig. 3 is a fragmentary front elevation of the smoke-box and parts of the system; Fig. 4 is a front elevation of a casting forming a part of the heater; and, Fig. 5 is a sectional view on line *y*—*y* of Fig. 4.

The boiler *a*, having the flues *b* and flue-sheet *c*; smoke-box *d*; steam-pipe *e* leading from the boiler through the smoke-box; blast-pipe *f* and petticoat-pipe *g*; deflector-plate *h* extending from the flue-sheet above the flues at a forward incline to a horizontal plane somewhat below the upper end of the blast-pipe, then forwardly in said plane and then downwardly at a forward incline; a screen *i* for permitting the gases and smoke from the flues, after having been deflected downwardly by the deflector-plate and so caused to enter chamber *j* (forward of said deflector-plate and screen) at the bottom thereof and to traverse the same before escaping at the opening *k* leading to the stack (not shown), are or may be all substantially the same as in constructions now commonly used.

To the front of the smoke-box is hinged the usual door *l* adapted to be held closed by the cross-bar *m* which rests at its ends in the brackets *n* and affords the necessary purchase for a bolt *o* penetrating the same and the door and having on its inner end a T-head entered through a slot in the cross-bar and its outer end threaded and carrying the nut *p*, provided with a lock-nut *q*, for drawing the door against its seat, all in a well-known manner.

In the cylindrical wall of the smoke-box near its front end are arranged the diametrically opposed bearing members *r* and *s* to the former of which is attached the supply pipe *t* leading from any suitable means, such

as an injector or feed water pump, for forcing the water through the feed-water heating system into the boiler, the same having a check-valve *u*, and to the latter of which is attached the pipe *v* which delivers the water to the boiler at any suitable point and has the check-valve *w*. Check-valves *u* and *w* respectively prevent pressure generated in the heater from acting back toward the injector through pipe *t* or the boiler steam escaping through pipe *v* should the heater burst or leak. Pipe *t* may have a branch *t'* leading directly to the boiler, said pipe and its branch having valves *t''* whereby the alternative feeding of the water to the boiler, indirectly through pipe *t* and the heater or directly through branch *t'*, may be controlled. The said members *r* and *s* receive the tubular trunnions of the heater now to be described:

The casting *x* (Fig. 4) has an upright hollow body-portion and an upper and a lower pair of hollow symmetrical arms, the arms of each pair projecting laterally from said body-portion in opposite directions. The upper and lower arms at each side of said body-portion of the structure *x* are connected by the rows of parallel tubes *y*, there being in the present case six rows (front to rear) of ten tubes each. The heater is divided into two distinct circulating branches by a vertical wall *z* extending from top to bottom of the interior of said body-portion of structure *x*, at each side of which is a series (extending front to rear) of six vertical passages 2 each a complement of the passages of a row of tubes. The flow is upwardly through the foremost innermost passage (2), then downwardly through the next (same row), then alternately upwardly and downwardly through the other passages of that row and finally up through the last; then rearwardly to and down through the outermost passage of the next row, then alternately upwardly and downwardly through the remaining passages of that row, and finally down through the last thereof; then rearwardly again, and so on through each row until all have been traversed. To accomplish this the arms are provided with the longitudinal walls 3, each arranged in a plane between two rows of tubes, and with the transverse walls 4 arranged in each arm in planes between every two passages, the walls 4 of the upper arm being staggered relatively to those of the lower or complementary arm; where the flow is rearwardly from one to the next row of passages, as at the outer end of the upper arm and the base of the body-portion of structure *x*, ports 5 and 6 (Figs. 2 and 1) are provided, and further, since otherwise the flow through the rearmost passage 2 would be downward instead of upward, the innermost tube of the last row is omitted and a port 2^a provided

to allow the water passing downwardly through the next innermost tube to enter said passage 2 at the bottom thereof. Each half of the heater is a true counterpart of the other.

The expanding of the tubes in forming the joints between their ends and the arms where they are fitted into the latter may be accomplished by removing the screw-plugs 7, alined with the tubes. Thus the assembling 75 of the parts of and repairing of the heater may be readily effected.

Projections 8 and 9 are cast on the lower and upper ends of the body-portion of structure *x* and include trunnions 10 and 11 respectively journaled in bearing members *r* and *s*, which have suitable means, including the glands 12, for giving the joints thus formed the character of stuffing-boxes. Each projection has a passage 13 (14) leading 80 through its trunnion to (from) the two passages 2 of the front (back) row of passages. Thus, water entering the lower passage 13 is divided, part going through one and part through the other of the aforesaid circulating branches, the two streams merging in 85 passage 14. Each trunnion has its axis coincident with a line *z*—*z* constituting the balance-axis of the heater (passing also through its center of gravity in the present 90 case), that is to say, a line with reference to which the inertia of the mass at one side thereof equals that of the mass at the other side thereof with respect to the forward and backward motion of the locomotive.

With the heater (whose area approximates that of the interior of the smoke-box, whereas its front-to-rear thickness is appreciably less, as shown) supported in bearings in the manner stated it will be apparent that whenever it is necessary to have access to the interior of the smoke-box for any purpose, having first swung the deflector 16 (hereinafter described) downwardly out of the way, the heater may be swung to a position more 100 or less at right angles to that shown by solid lines in the drawings, leaving clearance at both sides of it for the workman to enter; to increase the room he may then swing the heater back to the normal position. When 110 in use the heater may be held in the normal position by the clips 15 removably secured at some accessible point near the front of the smoke-box. The heater is placed sufficiently 115 near the front of the smoke-box so as not to interfere with the parts back of the same when it is turned.

The means for varying the course of the smoke and gases relatively to the heater is herein shown as a deflector 16 pivoted on a 125 horizontal axis afforded by a shaft 17 at the back thereof journaled in suitable bearings in proximity to the forward portion of the deflector-plate *h*, the shaft having an exterior arm 19 for turning it and the deflector 130

to any desired position, to be there held in any suitable way, as by a pin 20 passed through the arm and one of the holes of a curved bracket 21.

5 I claim:

1. In combination, with a smoke-box having an opening in the outer end thereof, a feed-water heater pivotally arranged in the smoke-box and having its pivoting axis extending transversely of the smoke-box and substantially coincident with a line extending centrally through the heater.

10 2. In combination, with a smoke-box having an opening in the outer end thereof, a feed-water heater pivotally arranged in the smoke-box and having its pivoting axis extending transversely of the smoke-box and substantially coincident with the balance-axis of the heater.

15 3. In combination, with a smoke-box having an opening in the outer end thereof, a feed-water heater pivotally arranged in the smoke-box and having its transverse area approximating the transverse area of the smoke-box and its front-to-rear thickness appreciably less than said area of the smoke-box, the pivoting axis of the heater extending transversely of the smoke-box and substantially coincident with a line extending

20 centrally through the heater.

25 4. In combination, with a smoke-box having an opening in the outer end thereof, a feed-water heater pivotally arranged in the smoke-box and having its transverse area approximating the transverse area of the smoke-box and its front-to-rear thickness appreciably less than said area of the smoke-box, the pivoting axis of the heater extending transversely of the smoke-box and substantially coincident with the balance-axis of the heater.

30 5. In a feed-water heating system, a feed-water heater having an inlet and an outlet arranged at opposite points thereof and substantially symmetrical portions projecting laterally with reference to a straight line connecting said inlet and outlet and each

35 having a tortuous water-conducting branch communicating at one end with the inlet and at the other with the outlet.

50

6. In a feed-water heating system, a feed-water heater having an inlet and an outlet arranged at opposite points thereof and substantially symmetrical tortuous water-conducting branches projecting laterally with reference to a straight line connecting said inlet and outlet and each communicating at one end with the inlet and at the other end with the outlet.

55

7. In a feed-water heating system, a feed-water heater having an inlet and an outlet arranged at opposite points thereof and substantially symmetrical portions projecting laterally with reference to a straight line connecting said inlet and outlet and each having a tortuous water-conducting branch communicating at one end with the inlet and at the other end with the outlet, each branch including a plurality of parallel rows of

60

70 passages.

8. In combination, with the boiler and smoke-box, the latter having an outlet for the smoke and gases entering the smoke-box from the boiler, a feed-water heater arranged in the smoke-box in spaced relation to the boiler, and means for directing toward the heater the smoke and gases flowing through the smoke-box including a deflector adjustable to different deflecting angles.

75

9. In combination, with a smoke-box having an opening in the end thereof, a feed-water heater pivotally arranged in and having its pivoting axis extending transversely through the smoke-box and a pivoting bearing at each point where said axis penetrates the wall of the smoke-box, and inlet and outlet connections connected with said heater respectively at the bearings thereof.
